Primary Examiner — Rebekah A Caruso*Assistant Examiner* — Cole Sanders Holman(74) *Attorney, Agent, or Firm* — Notaro, Michalos & Zaccaria P.C.(57) **CLAIM**

The ornamental design for a box PC, as shown and described.

DESCRIPTION

FIG. 1 is a top, front, right perspective view showing our design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the figures depict portions of the box PC that form no part of the claimed design.
